CLAIM

The ornamental design for an air exhaust manifold for cadaver table, as shown and described.

DESCRIPTION

FIG. 1 is a right front perspective of an air exhaust manifold for cadaver table showing my new design;

FIG. 2 is a front elevational view, thereof;

FIG. 3 is a rear elevational view, thereof;

FIG. 4 is a top plan view, thereof;

FIG. 5 is a bottom plan view, thereof;

FIG. 6 is a left hand side elevational view, the right hand side elevational view being substantially a mirror image thereof; and,

FIG. 7 is a front elevational view as in FIG. 2, but with the slidible vent cover in an alternate position.

FIG. 1.

FIG. 2.

FIG. 3.

FIG. 4.

FIG. 5.

FIG. 6.

FIG. 7.
